COUNTER MAT

Alfred William Fletcher, Wirral, England, assignor to The Moreton Engineering Company Limited, Liverpool, England

Filed June 29, 1973, Ser. No. 374,998

Claims priority, application Great Britain Jan. 4, 1973

Term of patent 14 years

Int. Cl. D7—99

U.S. Cl. D7—188

-FIG. 3-

-FIG. 4-

-FIG. 5-

-FIG. 6-

-FIG. 7-

-FIG. 8-

-FIG. 9-

FIG. 1 is a plan view of counter mat showing my new design;

FIG. 2 is a bottom plan view thereof;

FIG. 3 is a section along the line 3-3 of FIG. 1;

FIG. 4 is a front view thereof;

FIG. 5 is a rear view thereof;

FIG. 6 is a view from one side thereof;

FIG. 7 is a view from the other side thereof;

FIG. 8 is an enlarged section along the line 8-8 of FIG. 1; and

FIG. 9 is an enlarged section along the line 9-9 of FIG. 1.

I claim:

The ornamental design for a counter mat, substantially as shown and described.
